(57) **CLAIM**

The ornamental design for the phone pocket purse, as shown and described.

DESCRIPTION

FIG. 1 shows a perspective view of the phone pocket purse.

FIG. 2 shows a front view of the phone pocket purse.

FIG. 3 shows a back view of the phone pocket purse.

FIG. 4 shows a left side plain view of the phone pocket purse and the right view is a mirror image of the left side view.

FIG. 5 shows a top view of the phone pocket purse; and,

FIG. 6 shows a bottom view of the phone pocket purse.

The broken lines showing the portions of a chain handle are for the purposes of illustrating environment and forms no part of the claimed design.
